UNITED STATES PATENT OFFICE.

ALFRED INGRAM AND HARRY INGRAM, OF BROOKLYN, NEW YORK, ASSIGNEES TO
INGRAMS INCORPORATED, OF BROOKLYN, NEW YORK, A CORPORATION OF NEW
YORK.

CLOSURE FOR JARS, BOTTLES, AND OTHER RECEPTACLES.

1,353,400.

Specification of Letters Patent. Patented Sept. 21, 1920.

Application filed July 5, 1917, Serial No. 178,597. Renewed January 27, 1920. Serial No. 354,518.

To all whom it may concern:

Be it known that we, ALFRED INGRAM and HARRY INGRAM, citizens of the United States, and residents of Brooklyn, in the 5 county of Kings and State of New York, have invented certain new and useful Improvements in Closures for Jars, Bottles, and other Receptacles, of which the following is a specification.

10 The invention pertains more particularly, although not exclusively, to closures of the screw cap type adapted for sauce and catsup and other receptacles.

We present our invention as embodied in 15 a screw cap comprising a threaded barrel portion and a top portion having a depending central part bearing on its side a gasket, said depending portion and gasket being adapted to be forced in the mouth of the 20 receptacle so that the gasket may seal against the inner upper edges of said mouth. We preferably form a groove around the upper inner edges of the barrel portion of the cap to receive the outer peripheral edges 25 of the top of the cap, there preferably being a loose connection between said barrel portion and said top so that when the barrel portion is screwed downwardly upon the neck of a bottle and the gasket has engaged

30 the edges of the bottle mouth, said top may have a direct downward movement without rotating while the barrel portion is being screwed downwardly to effect a tight seal. The gasket is of special construction in that 35 it is a ring or band of rubber or other suitable packing material having a flat upper edge, a flat inner wall to engage the depending portion of the top of the cap, and an outer surface which is in part parallel with 40 the inner surface of the ring or band and has an inwardly beveled lower edge portion to engage the inner edges of the mouth of the bottle.

The invention will be fully understood 45 from the detailed description hereinafter presented, reference being had to the accompanying drawings, in which:

Figure 1 is a vertical section through a portion of the neck of a bottle with the cap 50 of our invention applied thereto preparatory to being screwed downwardly upon said neck so as to seal the bottle;

Fig. 2 is a side elevation, partly broken

away and partly in section, of the neck of the bottle, with the cap of our invention 55 screwed downwardly thereon and sealing the mouth thereof;

Fig. 3 is a bottom view of the cap detached from the bottle, and

Fig. 4 is a central vertical section through 60 a modified construction of the cap.

In the drawings, 5 denotes the neck of the bottle, 6 slightly convexed inner edges around the mouth thereof, 7 a screw thread of usual character formed directly upon the 65 neck of the bottle, 8 the contents of the bottle, and 9 the cap of our invention.

The cap 9 comprises a cylindrical or barrel portion 10 grooved in its lower walls, as at 11, to engage the thread 7 formed on 70 the neck of the bottle, a top 12 having a depending central portion 13 and a gasket 14 applied upon the exterior sides of said depending portion 13. The top 12 is of disk outline, and at its peripheral edges is 75 held within a groove 15 formed by flanging the upper edges of the barrel portion 10 outwardly below and then inwardly over said edges of the top 12. The barrel portion 10 and top 12 will preferably be 80 formed from sheet metal and the connection between the barrel portion 10 and top 12 will be sufficiently free to permit the barrel portion 10 to be screwed upon the neck of the bottle without rotating the top 12 so 85 that ordinarily when the gasket 14 engages the edges 6 of the mouth of the bottle, the resistance created against rotary motion of the top will result in the further downward movement of the barrel portion 10 exerting 90 a direct downward pull on the top 12 so that the central portion 13 of said top and the gasket 14 may move downwardly within the mouth of the bottle without being 95 caused to rotate within said mouth. The depending portion 13 of the top 12 is cylindrical, and upon the sides of said portion 13 is placed a gasket 14 which is of special character and extends from the lower surface of the top 12 to about the lower edge 100 of the depressed portion 13. The gasket 14 is a continuous ring or band of rubber or other suitable packing material and has an inner flat wall engaging the wall of the depressed portion 13, a flat top edge to 105 engage the surface of the top 12, an upper

outer flat surface, and a lower inwardly and downwardly beveled surface 16. We regard the form of the gasket 14 of considerable importance in respect to its efficiency 5 in creating a proper inner seal and also in that when the cap is screwed downwardly upon a bottle neck the lower edge of the gasket may readily enter the mouth of the bottle and said gasket, above its beveled 10 portion 16, may afford a proper sealing shoulder to firmly seat against the inwardly curved edges 6 at the mouth of the bottle, the parts taking the position shown in Fig. 2 after the cap has been screwed downwardly 15 upon the neck of the bottle. The efficiency of the gasket 14 as a sealing medium will be readily apparent from an inspection of Fig. 2, in which it may be seen that the gasket is compressed against the 20 surface 6 at the mouth of the bottle and is also under pressure against the sides of the depressed portion 13 of the top and also against the lower surface of said top adjacent to said portion 13.

25 The construction of cap shown in Fig. 4 differs from the caps shown in Figs. 1 and 2 in that it is formed in one integral piece of metal or other suitable material in lieu of having the top and skirt or barrel portions 30 in separate pieces, with said skirt or barrel portion rotatable around the top portion. In Fig. 4 we number the cap as a whole 20, and said cap comprises the skirt or barrel portion 21 to be connected with the neck of 35 a bottle, a top 22 having a central depending portion 23, and a gasket 24 applied upon the side of said depending portion 23 and being of exactly the same character and shape as the gasket 14 hereinbefore specifically described. The part 23 of the top 40 22 corresponds with the portion 13 of the top 12. The construction shown in Fig. 4 will, therefore, be fully understood without further specific description.

45 We have shown and described preferred embodiments of our invention without intending to limit the same unduly thereto, since we are aware that the cap may be variously modified within the scope and spirit 50 of our invention. We, therefore, desire to claim the invention broadly.

What we claim as our invention and desire to secure by Letters Patent, is:

1. A closure comprising an exterior barrel or skirt portion to pass downwardly over the neck of a receptacle, a top comprising a lateral portion extending annularly over the rim of the receptacle to said barrel portion and a depending central part adapted to pass downwardly into the mouth of the receptacle, and a sealing gasket closely encircling the side of said depending portion

tion and having a downwardly and inwardly beveled lower edge.

2. A closure comprising an exterior barrel or skirt portion to pass downwardly over the neck of a receptacle, a top comprising a lateral portion extending annularly over the rim of the receptacle to said barrel portion and a depending central part adapted to 65 pass downwardly into the mouth of the receptacle, and a sealing gasket closely encircling the side of said depending portion and having a downwardly and inwardly beveled lower edge, said barrel or skirt portion and said top being in independent parts interengaged at their adjoining edges and said barrel or skirt portion being rotatable around the outer edges of said top.

3. A closure comprising an exterior barrel or skirt portion to pass downwardly over the neck of a receptacle, a top comprising a lateral portion extending annularly over the rim of the receptacle to said barrel portion and a depending central part 80 adapted to pass downwardly into the mouth of the receptacle, and a sealing gasket closely encircling the side of said depending portion and extending from said lateral portion to substantially the lower end of 85 said depending portion and having a flat inner wall, a flat top edge and an outer wall whose upper portion is parallel with said inner wall and whose lower portion is beveled downwardly and inwardly.

4. In combination with a receptacle, a closure therefor comprising an exterior barrel or skirt portion to pass downwardly over the neck of a receptacle, a top comprising a lateral portion extending annularly 95 over the rim of the receptacle to said barrel portion and a depending central part adapted to pass downwardly into the mouth of the receptacle, and a sealing gasket closely encircling the side of said depending portion and having a downwardly and inwardly beveled lower edge, said barrel or skirt portion and said top being in independent parts interengaged at their adjoining edges and said barrel or skirt portion being rotatable around the outer edges of 100 said top, and said barrel portion and receptacle having interengaging portions for 105 detachably securing the closure on the receptacle.

Signed at New York city, in the county of New York and State of New York, this 3rd day of July A. D. 1917.

ALFRED INGRAM.
HARRY INGRAM.
